UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

LINE-CASTING MACHINE.

961,799.

Specification of Letters Patent. Patented June 21, 1910.

Application filed May 25, 1909. Serial No. 498,249.

To all whom it may concern:

Be it known that I, JOHN R. ROGERS, of the borough of Brooklyn, county of Kings, and State of New York, have invented a new and useful Improvement in Line-Casting Machines, of which the following is a specification.

My invention has reference to line casting machines of the general class represented in Letters Patent of the United States No. 436,532. In these machines circulating matrices, stored in a magazine, are released by fingerkeys in the required order, composed in line, and the line transferred to the face 10 of a slotted mold, which is then filled with molten metal to produce a slug or linotype on which type characters are formed by the matrices; the matrices being thereafter returned through a distributing mechanism 15 to the magazine channels from which they were discharged.

The object of my invention is to provide a machine of this general class, adapted to carry more than one font of matrices, so 20 that type faces differing in size or in style may be produced at will, and so that each line may be composed of matrices from one or both magazines, and the distribution of the matrix lines carried on continuously 25 without reference to the character of the matrices therein. To this end I employ two magazines, arranged to deliver matrices through intermediate means to a single assembler in which the line is formed. I arrange the magazines in parallel, or substantially parallel lines, with the escapement devices for releasing the individual matrices on their inner or proximate faces that is to say, in the space between the magazines; 30 and for the purpose of operating the escapements of one magazine or the other at will, I employ a single series of reeds, connected with the keyboard and mounted in a movable guide, so that they may be adjusted to act 35 upon one series of escapements or the other at will. For the purpose of distributing the matrices, I extend along the top of each magazine a distributor of the Mergenthaler type such as represented in Letters Patent 40 of the United States No. 347,629, each consisting of a horizontal bar provided with longitudinal permuted teeth, to sustain and carry the toothed matrices, which are moved along the bar by adjacent screws. The distributor of one magazine has more teeth, or

an arrangement different from that of the other distributor, and the matrices delivered to the respective magazines are toothed to correspond. All of the matrices are delivered to the distributor of the first magazine, 60 which delivers to said magazine the matrices belonging therein, while the matrices for the second magazine travel the entire length of the bar and are delivered therefrom at one end, where they are carried mechanically to 65 the second distributor, along which they travel in a reverse direction, and by which they are delivered into their appropriate magazine channels.

With the exception of the parts forming 70 the subject of the present invention, and specifically described and claimed herein, the machine may be in all respects of the same construction as the commercial Mergenthaler machine of the present day, or of any other 75 appropriate construction.

I have limited the accompanying drawings to those parts of the machine which are necessary to an understanding of my invention.

Figure 1 is a front elevation of the upper part of the machine. Fig. 2 is a vertical cross section from front to rear on the line 2—2, with portions of the magazine shown in section. Fig. 3 is a diagram showing the manner in which the distributor screws are driven. Fig. 4 is a vertical cross section on the line 4—4 of Fig. 1, showing the mechanism for transferring the matrices from the first to the second distributor. Fig. 5 is 80 a cross section of the first distributor bar, having eight pairs of teeth, and a corresponding matrix. Fig. 6 is a cross section of the second distributor bar, with seven teeth, 85 in connection with a matrix having eight teeth. Fig. 7 is a cross section of the first distributor bar with eight teeth, showing a matrix thereon with all its teeth disengaged, in position to escape. Fig. 8 is a perspective view illustrating matrices of different fonts. 90 Fig. 9 is a perspective view showing in outline the two distributors and the matrix feeding and transferring devices. Fig. 10 is an outline perspective showing the manner in 95 which the matrices are delivered to the second distributor. Fig. 11 is a vertical section on the line 11—11 of Fig. 1.

Referring to the drawings, A represents a main frame, which may be of any suitable form; B and B¹ two inclined magazines 100

mounted on the main frame, one over the other, and each adapted to carry a font or set of matrices, C and C¹. The magazines may be of the usual Mergenthaler construction, 5 consisting of two parallel plates, grooved in their inner faces to receive and guide the upper and lower edges of the matrices, as shown; or they may be of any other appropriate construction. The magazines shown 10 in the drawing differ from those of the ordinary Mergenthaler machines in that instead of having vertically curved throats or entrances at the upper ends, they are continued in straight lines to their upper extremities—the upper lines of the magazines being at a 15 common level so that the matrices may be delivered directly therein. The discharge of the matrices from the magazines, one at a time in the order in which they are required, 20 will be effected by escapement devices of any suitable form connected with the keyboard mechanism, as well understood in the art. I prefer, however, the construction shown in Fig. 11, in which the upper magazine is provided on the under side with the escapement levers D, while the lower magazine is provided on its upper side with corresponding escapements, D¹, each escapement consisting 25 of a centrally pivoted lever carrying at opposite ends two fingers, which are projected alternately into the magazine by the vibration of the lever; so that the matrices are released one at a time. The escapement levers of the two series have their lower 30 ends terminated side by side and exposed, as shown in Fig. 11, and they are actuated by vertical sliding reeds, E, equal in number to the escapements in one magazine. These 35 reeds may be actuated by a keyboard mechanism such as represented in Letters Patent of the United States to P. T. Dodge No. 530,931, or by any other suitable fingerkey mechanism, several of which are well known 40 in the art. The lower ends of the reeds will 45 contain a permanent connection with the keyboard, but the upper ends are mounted in a horizontally movable guide, F, connected to an angular hand lever, G, pivoted in the frame; so that by moving the lever the guide F may be shifted forward and backward, 50 and all of the reeds caused to actuate the escapements of the upper or lower magazine, as required. The matrices delivered from the magazine descend through two vertically 55 channeled guides or face plates, H and H¹, similar to those used on the commercial Mergenthaler machine. Below the respective face plates are arranged parallel inclined belts, I and I¹, by which the matrices are received and directed downward and to the upper ends of a forked guide, J, through 60 which they descend successively into the usual assembling elevator, K, in which they are assembled or composed in line under the influence of the usual star wheel or pusher, L.

It will be observed that the two series of escapements are located between the two magazines, and that the escapement operating reeds are seated between the two face plates and extended upward to a point between the magazines. This arrangement admits of the matrices from either or both magazines being directed at will to a common line in the assembler. From the assembler the matrix line will be transferred 75 to the casting mechanism, and thence to the second elevator, M, so-called, by which the line is lifted to the distributing mechanism above the magazines. As the casting and transferring mechanism can all be of ordinary construction, and are foreign to my invention, it is unnecessary to describe them herein.

Over the respective magazines I mount 80 at a common level or practically so the horizontal parallel distributor bars N and N¹, having their lower edges of V form, with horizontal teeth, varied in number or arranged at different points in the length of the bar, in the manner fully explained in 85 the Mergenthaler Patent No. 347,629. The first bar, N, is provided with eight teeth on each side, while the second bar is provided with seven teeth only.

The matrices for the respective magazines 90 are notched and toothed in the upper end in the usual manner, as shown in Fig. 8, except that the matrices for the upper magazine, received in the first distributor, are provided with seven pairs of teeth only, in 95 order that they may be discharged from the first distributor directly into the upper magazine; while on the other hand the matrices for the lower magazine are constructed with eight teeth each, in order that they may 100 travel the entire length of the first distributor bar, and then be delivered to the second bar.

Referring to Fig. 10, O and O¹ represent 105 the horizontal rails of the ordinary distributor box, shouldered at their forward ends; so that when the composed line of matrices is introduced horizontally, it will be sustained by the rails and arrested at the forward end by the shoulders.

P is the vertically movable finger by which 110 the matrices are lifted successively from the front end of the line, clear of the detaining shoulders, and into engagement with the feed screws, by which they are carried forward horizontally, so that their teeth will engage those of the distributor bar N at its left end.

Q is a stationary bar overlying the position 115 occupied by the matrix line, for the purpose of holding down all but the foremost matrix in the line.

R and R¹ represent the horizontal screws, 120 extended parallel with the distributor bars, three for each bar, in position to engage the 125

edges of the matrices and carry them along the bar toward the right to the points at which their teeth disengage and permit them to fall into the magazine below, in the manner well known in the art.

The teeth of the first distributor and its matrices will be formed in all respects like those in the ordinary single magazine Mergenthaler machine; so that the matrices for the upper magazine will be delivered directly thereto from the first distributor, N. The matrices C¹, of the lower magazine, however, by reason of their extra teeth at the top, will continue to engage the distributor bar N until they arrive at its right end, from which they escape. In other words, all the matrices intended for the lower or second magazine traverse the first distributor from left to right, where they are all discharged at one point. Arriving at this point, the matrices are received in a horizontal channel, S, extending beneath the rear distributor bar. As each matrix is thus received, it is acted upon by a horizontal slide, T, and pushed rearward to a position under the second distributor bar, and over a vertically reciprocating finger, U, by which it is raised into engagement with the screws of the second distributor, along which it is caused to travel to the points at which its teeth disengage; so that it may fall into the lower magazine.

It is to be noted that the foregoing devices serve to deliver the matrices positively and one at a time to the second distributor.

The various screws are connected by gearing, as shown in Fig. 3; so that while all the matrices are compelled to traverse the first distributor from left to right, the matrices transferred to the second distributor are carried along the same from right to left.

The lifting finger U may be operated in any suitable manner; for example, as shown in Fig. 10, by an angular lever, u, acted upon at one end by a cam, u¹, on the end of one of the distributor screws.

As the matrices are raised to the second distributor bar, they are guided and held forward in proper position by a pressure shoe, u², acted upon by a spring, u³, with suitable guiding devices on the opposite side, to insure the delivery of each matrix in proper position between the screws, where it is free to engage and travel along the distributor bar.

The horizontal transfer slide, T, may be actuated by any suitable means; for example, as shown in Fig. 4, by an angular lever, t, urged in one direction by a spring, t¹, and in the opposite direction by a cam, t², connected by gears with one of the distributor screws; so that the proper assembling of the parts is insured.

The operation of the machine is as follows: The lever G is adjusted to connect the

reeds F with the escapements of one magazine or the other, according to the style of type face demanded; fingerkeys being manipulated, as usual, to actuate by reeds E the escapements, and permit the matrices to descend from the magazines through the face plates to the guide J, whence they pass into the assembler, from which they are transferred to the casting mechanism. After the casting operation, the line is lifted and transferred horizontally to the rails O and O¹ on the distributor box, and urged forward against the stop shoulders. The finger P lifts the matrices successively, and they are transferred, as usual, to and along the bar N. The matrices of the first magazine escape directly from this bar, while those of the second magazine continue to the right end of the bar, where they fall successively into the path of the slide T, by which they are carried one at a time rearward over the finger U, which lifts them to the second distributor bar, N¹, along which they are carried in a reverse direction to their points of delivery, to the second magazine. The corresponding channels of the two magazines will contain matrices bearing like characters; that is to say, the same characters in different forms. For example, the left hand channel in both magazines may contain matrices for the letter "e." It follows, therefore, that the combinations of the second distributor bar must be arranged in the reverse order from those of the first bar, and that its matrices must have their combinations correspondingly arranged. In other words, the matrices which are discharged from the first position on the bar N will have the same combination as those which are discharged from the last position on the bar N¹; the matrices of the second bar having, however, the extra pair of teeth, preferably at the upper end.

While I have described herein my invention as embodied in a machine having two magazines, it will be obvious that the number involved may be extended to three or more magazines by the employment of a corresponding number of fonts of matrices, the matrices of the different fonts being differentiated as to the number or arrangement of their teeth, so that the matrices remaining after traversing the first, or the first and second distributors, may be transferred to a third, and so on indefinitely.

Having described my invention, I claim and desire to secure by Letters Patent:

1. In a line casting machine, two magazines, one overlying the other, two parallel distributors arranged to deliver matrices to the respective magazines, and matrices of two fonts differentiated as to their distributing teeth, in combination with means for delivering all the matrices to the first distributor, and positively acting means adapt-

- ed to deliver all the matrices not delivered to the first magazine one at a time to the second distributor.
2. In a line casting machine, two parallel distributor bars; two sets of toothed matrices, the teeth of one set being adapted to carry them the entire length of the first distributor; means for causing the individual matrices to traverse the first distributor in one direction; means for delivering the matrices which traverse the entire length of the first distributor, to the second distributor; and means for moving said matrices along the second distributor in a reverse direction.
3. In combination with the two parallel distributor bars N and N¹ at a common level, two fonts of matrices, differentiated as to their distributing teeth; means for delivering all the matrices to the first distributor; and a transverse carrier, located at the delivery end of the first distributor, to transfer the matrices one at a time to the receiving end of the second distributor.
4. In a line casting machine, the combination of the parallel toothed distributor bars N and N¹, the first having more teeth than the second; a font of matrices, toothed for release by the first bar; a second font of matrices, toothed to traverse the entire length of the first bar, and to be distributed by the second bar; means for delivering all the matrices to and along the first bar; means for transferring the matrices of the second font from the first bar to the second; and means for moving the transferred matrices in a reverse direction along the second bar.
5. In a line casting machine, two fonts of matrices representing like characters, the distributing teeth of the two fonts being arranged in reverse order; in combination with parallel distributor bars, having their teeth arranged in like manner; means for presenting all matrices to the first bar, and the matrices of the second font to the second bar; and means for moving the matrices along the respective bars in a reverse direction; whereby a matrix of one font, bearing a given character, will be discharged from one distributor at a point directly opposite the delivery of the corresponding matrix of the second font, from the other distributor.
6. In a line casting machine, two inclined magazines one overlying the other and both continued in straight lines to their upper ends, at a common level, in combination with two distributor bars over the respective magazines, one adapted to distribute the matrices in a reverse order from the other, means for delivering all the matrices to the first distributor, and means for delivering all the matrices which are not distributed by the first distributor to the second distributor.
7. In combination with the distributor bars N and N¹, a support, S, to receive the matrices delivered from the end of the bar N; a carrier, T, to transfer said matrices to a position beneath the second distributor, and a finger, U, to lift matrices to a second distributor.
8. The combination of the bars N and N¹; the adjacent feed screws, arranged to deliver matrices in reverse directions along the respective bars; and means for transferring matrices from the first bar to the second.
9. In combination with the two inclined magazines, two channeled face plates arranged to receive matrices from the respective magazines, an assembler, and a guide J adapted to deliver matrices descending through the two face plates to the assembler.
10. In combination, the inclined magazines; the channeled guides or face plates H and H¹; the conveyer belts I and I¹; an assembler, K; and the forked guide J, to deliver matrices from the respective magazines to a common line in the assembler.
11. In combination, two parallel magazines having escapements coöoperating with the respective magazines and located between them, a series of escapement actuating reeds, and means for shifting the reeds at will to disengage them from either series of escapements and engage them with the other.
12. In combination, the two inclined magazines; the intermediate escapements D and D¹, coöoperating with the respective magazines, said escapements each pivoted at the middle and exposed at the lower end; the upright reeds E; and a shiftable guide for said reeds; whereby they may be caused to directly actuate the escapements of the upper or the lower magazine at will.
- In testimony whereof I hereunto set my hand this 13th day of May, 1909, in the presence of two attesting witnesses.
- JOHN R. ROGERS.
- Witnesses:
E. J. LAMB,
JAMES J. PENDERGAST.
